CLAIM

The ornamental design for gear housing, as shown and described.

DESCRIPTION

FIG. 1 is a perspective view of a first embodiment showing our new design configured as a gear motor assembly with a motor and an output shaft shown in dotted line;

FIG. 2 is a top view thereof;

FIG. 3 is a front view thereof;

FIG. 4 is a back view thereof;

FIG. 5 is a left side view thereof;

FIG. 6 is a right side view thereof;

FIG. 7 is a bottom view thereof;

FIG. 8 is a perspective view of a second embodiment showing our new design configured as a reducer assembly with the input and output shafts shown in dotted line;

FIG. 9 is a top view thereof;

FIG. 10 is a front view thereof;

FIG. 11 is a back view thereof;

FIG. 12 is a left side view thereof;

FIG. 13 is a right view thereof;

FIG. 14 is a bottom view thereof;

FIG. 15 is a perspective view of a third embodiment showing our new design configured solely as a gearbox casing;

FIG. 16 is a top view thereof;

FIG. 17 is a front view thereof;

FIG. 18 is a back view thereof;

FIG. 19 is a left side view thereof;

FIG. 20 is a right side view thereof; and,

FIG. 21 is a bottom view thereof.

The items shown in dotted line in the various views of the Figures do not form a part of our inventive design and are not claimed herein.
